LOCOMOTIVE BOILER THROAT SHEET
CONSTRUCTION

George M. Wilson, Schenectady, N. Y.

Application October 14, 1933. Serial No. 693,691

5 Claims. (Cl. 122—58)

This invention relates to steam boilers of the type used in locomotives, and particularly to an improved throat sheet construction for such boilers.

5 An object of the invention is to provide an improved throat sheet construction for a locomotive steam boiler especially adapted to accommodate longitudinal contractions and expansions of the boiler.

10 A further object is to provide an improved throat sheet construction of the character aforescribed particularly adapted to facilitate circulation of water from one boiler section to another.

15 Other and further objects of and advantages achieved by the present invention will be apparent from the description of an approved exemplification thereof hereinafter set forth.

While the present invention is not confined to any particular design of throat sheet, the conventional design which is herein referred to contains features common to all designs subject to the improvements of the present invention.

In the conventional boiler of the type with 25 which the present invention is concerned, the forward margin of the fire box section and the rear margin of the barrel section are in direct engagement over substantially the upper half of the barrel section and the margins begin to diverge downwardly at substantially the horizontal center line of the barrel section. The purpose of 30 the throat sheet is to connect the respective margins extending downwardly from said horizontal center line, and to enclose the boiler between these margins. To accomplish this the 35 throat sheet is shaped at each side to provide a rearwardly extending flange, and in front to provide a forwardly extending flange, the rearwardly extending flanges being for connection with the forward margin of the fire box section and the 40 forwardly extending flange for connection with the rear margin of the barrel section throughout the converging portions of said margins at each side of the boiler.

45 To connect the converging margins it is necessary to warp the throat sheet between its flanges in a manner to produce reverse curves therein, in horizontal planes, and obviously where there is very little surface in comparison to the thickness

50 of the throat sheet, it is exceedingly difficult to impart the necessary warping without unduly taxing the sheet. The sheet diminishes in area gradually upwardly at each side as the flanges converge, and the gist of the present invention is 55 to enlarge the throat sheet at its upper side

portions and to thereby materially decrease the degree of abruptness of warping necessary at these portions for producing the required offset in the two flanges to position the flanges where they will respectively engage, one with the forward margin of the fire box section and the other with the rear margin of the barrel section.

In the exemplification of the invention hereinafter described the throat sheet is extended forwardly and the forwardly extending flange is consequently correspondingly extended forwardly, as is also the rear margin of the barrel section engaged by the forwardly extended flange.

Obviously, instead of this forward extension of the throat sheet, it can be extended rearwardly 70 by a corresponding rearward extension of the rearwardly extending side flanges and the forward margin of the fire box section, or if desired, the sheet can be extended both forwardly and rearwardly with corresponding appropriate 75 extensions of the flanges and margins. It is therefore to be understood that the appended claims unless otherwise restricted are intended to cover a throat sheet extended in any way that will enable the desired results that have been set 80 forth to be attained.

In the accompanying drawings, Figure 1 is a diagrammatic side elevation of a locomotive boiler including a throat sheet construction embodying the present invention; Fig. 2 is an enlarged, fragmentary, side elevation of the boiler shown in Fig. 1; Fig. 3 is a half front view of the structure shown in Fig. 2; Figs. 4 to 9 are horizontal, longitudinal, fragmentary, sectional views of the structure, taken on the lines IV—IV to IX—IX 90 inclusive, respectively, of Fig. 3; Fig. 10 is an enlarged, perspective view of the throat sheet of the present invention; and Fig. 11 is an enlarged, perspective view of the rear portion of the locomotive boiler barrel section to which the throat sheet of the present invention is attached.

The present invention is shown in connection with a locomotive steam boiler of the conventional type indicated generally by the numeral 1, which includes the usual fire box section 2 and barrel section 3 connected thereto at its forward end. Such boiler sections being old and well known in the art, a detailed description thereof will not be herein included.

The outer front sheet of the fire box section, 105 that is to say the throat sheet 4, (see particularly Fig. 10) comprises a body portion 5 which is disposed transversely of the boiler at the forward end of the fire box section and extends upwardly from the bottom of the fire box section until it 110

meets the bottom and sides of the barrel section 3 at the rear end thereof. Rivet holes 6 are provided in the lower margin of the portion 5 and this margin is secured by rivets (not shown) passed through these holes, into the fire box section mud ring, a portion of which is indicated at 7 in Fig. 10. The throat sheet is turned forwardly at the portion thereof above the body portion 5, engaging the bottom portion of the barrel section indicated at 8, and providing a curved flange 9 which is suitably secured to the portion of the barrel section indicated at 8 by rivets (not shown), registering rivet holes 10 and 11 being provided in the portion of the barrel section at 8 and the flange 9 respectively for this purpose. At the sides of the body portion 5, the throat sheet is turned rearwardly, providing substantially vertical, longitudinally extending, side flanges 12. The side flanges 12 extend from the bottom of the fire box section to the top of the throat sheet at a location approximately just above the center line of the barrel section. Rivet holes 13 are provided in the side flanges, and these flanges are secured to the outer side sheets 14 of the fire box section by means of rivets (not shown) passed through the holes 13 and corresponding holes 15 provided in the sheets 14.

The curved flange 9 extends upwardly at its opposite sides providing substantially vertical portions adjoining the upper portions of the flanges 12. The upper portions indicated at 16 of the throat sheet are extended forwardly, providing wings or extensions 17 which engage the sides of the barrel section, being curved in conformity therewith. Rivet holes 18 are formed in the wings 17 and in the upper margins of the throat sheet portions immediately adjacent thereto. The barrel section 3 is cut away at its opposite sides, below the barrel center line, as indicated at 19. Rivet holes 20 corresponding to the holes 18 are formed in the margins of the section 3 around the cutaway portions, where the wings 17 engage the barrel section, suitable rivets (not shown), being disposed through the holes 18 and 20, securing the parts together. As indicated at 21 rivet holes are provided around the entire rear margin of the upper portion of the barrel section 3, corresponding holes being provided in the adjacent fire box section sheet portions, and rivets (not shown) being passed through these holes, securing these adjacent portions together in the usual manner.

At approximately the center line of the barrel section, the side sheets 14 of the fire box section are tangent to the respective sides of the barrel section and the respective adjacent forwardly and rearwardly extending flange portions, at the opposite sides of the throat sheet, accordingly approach each other as they near this location, and are aligned with each other at this location as shown in Fig. 4. That is, on each side of the boiler the fire box sheet 14, the flange 12, the portion indicated at 16, and the barrel section side are in a substantially straight horizontal line at this location. It is just below this location that cracks in the throat sheet usually occur, as the result of expansions and contractions of the fire box section and barrel section.

It will be understood that the expansions and contractions of the boiler sections are due to heating and cooling and are greatest in a longitudinal direction. Thus, as the upper portions of the throat sheet form the connection, at this location, between the fire box section and the

barrel section, they must adjust themselves accordingly to accommodate these expansions and contractions. Such adjustments in throat sheet constructions of designs such as heretofore employed usually result in a weaving action, which sets up great strains in the throat sheet, and frequently results in cracking the sheet at the points of greatest strain.

In Figs. 4 to 9 there are illustrated sections showing the curves of the throat sheet construction of the present invention at various locations throughout a zone extending downwardly from substantially the center of the barrel section. In Figs. 5 to 8 inclusive, there are indicated, in broken lines, the curves of a throat sheet of the usual type, heretofore employed at the various respective locations, and in Fig. 2 there is indicated by broken lines the usual location of the lap joint between the throat sheet and barrel section. It will be apparent that the throat sheet construction of the present invention is lengthened, that is, it is provided with the wings 17 at the portions thereof which connect with the barrel section from the barrel section center line to a line some distance below, covering a zone 100 where the greatest strains occur. Thus, while as in usual practice the throat sheet of the present construction is connected to the barrel section by rivets, in the present instance the riveted connections of the portions covering a zone immediately 105 below the barrel section center line are moved further forward than in usual practice. Above and below the wings 17, the connection is brought back to the usual positions, that is, it conforms with the shape of the throat sheets commonly 110 used.

It is noted that the usual practice is followed in the securing of the throat sheet with its side flanges placed at the inner sides of the outer fire box sheets and its forwardly extending flange 115 placed at the outer side of the barrel section, as clearly shown in Figs. 4 to 9 inclusive.

By elongating the throat sheet in this manner, greater space is provided in which the directions of the curvature of the throat sheet at the sides 120 of the boiler must be changed, and thus curves of easier sweep than those heretofore employed in throat sheets, may be used. With such construction it will be apparent that the throat sheet may more freely adjust itself in order to 125 accommodate the longitudinal expansions and contractions hereinbefore mentioned, so that cracking of the sheet as a result of such expansions and contractions will be avoided or reduced to a minimum.

Further, by virtue of this relative gradual curvature of the throat sheet, circulation of water from the barrel section to the fire box section past the throat sheet will be facilitated, that is to say the circulation will not be obstructed by 130 abrupt irregularities in the contour of the throat sheet, such as are present in designs of the prior art.

While there has been hereinbefore described an approved embodiment of the present invention, it will be apparent to those skilled in the art that many and various changes and modifications in degree, form, structure and arrangement may be made without departing from the spirit of the invention and it will be understood that 140 all and any such changes and modifications are contemplated as a part of the present invention.

The invention claimed, and desired to be secured by Letters Patent is:

1. A steam boiler comprising a fire box section;

- a barrel section disposed forwardly of said fire box section with its bottom higher than the bottom of said fire box section; and a throat sheet connecting said sections having a body portion transversely disposed at the forward end of said fire box section and extending upwardly from the bottom thereof to said barrel section, side flanges at the opposite sides of said body portion extending upwardly beyond said body portion, said side flanges extending rearwardly of said body portion and being connected with the respective sides of said fire box section, and a curved flange at the top of said body portion having side portions extending upwardly beyond said body portion adjacent the upper portions of the respective side flanges, said curved flange extending forwardly of said body portion and being connected with the bottom and sides of said barrel section, said side portions of said curved flange and the respective adjacent rearwardly extending side flanges approaching alignment with each other as they approach the horizontal center line of said barrel section and said throat sheet being widened between each of said side portions of said curved flange and its adjacent side flange above said body portion to provide relatively gradually diminishing curves therein from the body portion upwardly. 5
2. A throat sheet comprising a body portion adapted to be transversely disposed at the forward end of a boiler fire box section and to extend upwardly from the bottom thereof to a boiler barrel section; side flanges at the opposite sides of said body portion extending upwardly above said body portion, said side flanges extending rearwardly of said body portion for engagement with the respective sides of said fire box section; and a curved flange at the top of said body portion having side portions extending upwardly beyond said body portion adjacent the upper portions of the respective side flanges, said curved flange extending forwardly of said body portion for engagement with the bottom and sides of said barrel section, said upwardly extending side portions of said curved flange adjoining the upper portions of said respective side flanges and being extended further forwardly than the lower portion of said curved flange and said rear end of said barrel section having a contour corresponding to the contour of said curved flange, whereby the connections of said upwardly extending side portions of said curved flange with the respective sides of said barrel section are disposed forwardly of the connection of the lower portion of said curved flange with said barrel section. 10
4. A throat sheet for connecting a semi-box-shaped fire box boiler section and a barrel boiler section, adapted to extend from the bottom of the fire box section to substantially the horizontal center line of the barrel section, comprising oppositely disposed side margins for attachment to said fire box section and a margin forward of said side margins for attachment to said barrel section, the upper side portions of said sheet being widened between said margins. 15
5. A throat sheet for connecting a semi-box-shaped fire box boiler section and a barrel boiler section, adapted to extend from the bottom of the fire box section to substantially the horizontal center line of the barrel section, comprising oppositely disposed side margins for attachment to said fire box section and a margin forward of said side margins for attachment to said barrel section, the upper portions of said last mentioned margin being extended forwardly providing thereby widened upper portions of said sheet. 20
3. A steam boiler comprising a fire box section; a barrel section disposed forwardly of said fire box section with its bottom higher than the bottom of said fire box section; and a throat sheet connecting said sections having a body portion transversely disposed at the forward end of said fire box section and extending upwardly from the bottom thereof to said barrel section, side flanges at the opposite sides of said body portion extending upwardly above said body portion, said side flanges extending rearwardly of said body portion and being connected with the respective sides of said fire box section, and a curved flange at the top of said body portion having side portions extending upwardly beyond said body portion adjacent the upper portions of the respective side flanges, said curved flange extending forwardly of said body portion and being connected with the bottom and sides of said barrel section at the rear end thereof, said upwardly extending side portions of said curved flange adjoining the upper portions of said respective side flanges and being extended further forwardly than the lower portion of said curved flange and said rear end of said barrel section having a contour corresponding to the contour of said curved flange, whereby the connections of said upwardly extending side portions of said curved flange with the respective sides of said barrel section are disposed forwardly of the connection of the lower portion of said curved flange with said barrel section. 25
